UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

REFRIGERATOR-CAR-DOOR-OPERATING MECHANISM.

Application filed November 23, 1925. Serial No. 70,752.

This invention relates to improvements in refrigerator car door operating mechanisms.

One object of the invention is to provide a simple and efficient arrangement of door 5 operating mechanism, especially adapted for refrigerator cars, for forcing the doors to tightly closed position and for holding the same closed, and which will also be effective in starting the door opening operation.

10 A more specific object of the invention is to provide a mechanism of the character described, especially designed for operating doors of the swinging type, including a rotary operating shaft having an offset portion 15 functioning as a door operating crank arm in conjunction with a transmitting member pivotally connected to the crank arm intermediate its ends, said member having one end movably secured to the door and having 20 its other end provided with a portion adapted to coact with a fixed keeper secured to the door frame.

Other objects and advantages of the invention will more fully and clearly appear 25 from the description and claims hereinafter following.

In the drawings forming a part of this specification, Figure 1 is a side elevational view of a portion of a refrigerator car, showing 30 my improvements in connection therewith. Figure 2 is an enlarged, vertical, sectional view, partly broken away, corresponding substantially to the line 2—2 of Figure 1. Figure 3 is a horizontal, sectional view, corresponding substantially to the line 3—3 of 35 Figure 1. Figure 4 is a horizontal, sectional view through one of the end portions of the operating shaft taken along the lower edge of the right hand door, substantially on the line 4—4 of Figure 2. And Figure 5 is a transverse sectional view of the bearing bracket taken substantially on the line 5—5 of Figure 3.

In said drawing, the car is shown as provided with a door frame 10 and two pivoted doors 11 and 12, having meeting beveled edges in the usual manner. As is customary in refrigerator cars, insulation or packing is employed between the meeting edges of the 50 doors themselves and around the sides and top. The doors 11 and 12 are mounted to swing about vertical axes, being supported by suitable hinges 13.

As shown, the improved door operating 55 mechanism comprises, broadly, an operating

shaft A provided with two end castings B—B, and an operating handle C; upper and lower bearing brackets D—D; transmitting elements E—E; and upper and lower keepers F—F.

The operating shaft A preferably is in the form of a flat bar of rectangular cross section, having the handle or lever C pivoted thereto by a pin 20. The castings B are disposed respectively at the upper and lower 60 ends of the shaft A. Each of the end castings B, as shown, is preferably in the form of a crank having a cylindrical operating portion 21 aligned with the axis of the operating shaft, and an offset cylindrical end 65 portion of crank arm 22. Each casting B is formed with a head 23 at the inner end of the journal portion 21, which is vertically slotted and indicated at 24 for the reception of the corresponding end of the shaft A, to 70 which it is fixed by rivets 25 or any other suitable securing means.

The bearing brackets D—D, which are of like construction, are respectively mounted at the upper and lower ends of the door 75 11 adjacent the free edge thereof. Each of the brackets D comprises an inner plate 26 provided with a half bearing seat 27, and cooperating with said inner member 26 is an outer plate 28 provided with a half bearing 129, the two members together providing a journal opening for the journal section 21, the plates 26 and 28 being secured to the door by bolts 29 or other suitable means.

The transmitting members E—E also are of like construction, one of the same being associated with each of the end members B—B of the shaft A. Each transmitting member is in the form of an elongated link or lever 30, provided with a slightly wider 90 portion 31 adjacent one end which has a journal opening 32 for the pivotal reception of the cylindrical crank pin 22. The outer end 33 of the transmitting member 30 is provided with a cylindrical pin 34 on its 100 outer face for co-operation with the related keeper F, as hereinafter more particularly described. The opposite end portion 35 of the transmitting member 30 is also provided with bosses 36 on its opposite sides which are 105 movably connected in a housing 37 mounted upon the door. Each housing 37 is preferably of integral construction and is secured to each edge of the door a slight distance 110 outwardly of the adjacent bearing bracket D

2
by means of bolts 38 or other suitable securing means. The housing is provided with a slot 39 extending longitudinally therethrough to permit the passage of the transmitting member 30, the upper and lower walls of the housing above and below the slot 39 being provided with channels 40 which terminate at a point approximately between the ends of the housing to provide 5 offsets, as indicated at 41, so that while free sliding movement of the member 31 is permitted in the housing within predetermined limits, the outward movement of the member 30 is arrested when the bosses 36 come 10 into engagement with the ends of the channels 40 as clearly shown in Figures 4 and 5. The slot 39 diverges outwardly as indicated at 42 to permit the required swinging movements of the member 30 and the face of 15 the door member cut out as indicated at 43 to permit said swinging movements as will be appreciated.

The upper and lower keepers F—F which are mounted upon the lintel and threshold 20 of the door frame, are of substantially similar construction, each including vertically disposed flange-like portions 44 by which the keeper is bolted to the car. Each keeper is provided at one side with a recess 45, 25 which extends substantially parallel to the face of the door frame through the major portion of its length, said slot or recess opening outwardly at a relatively sharp angle, as indicated at 46, being thereby adapted for 30 the reception of the pin 34 upon the transmitting member 30.

The flange portion 44 of the lower keeper F is extended to the left, as shown in Figure 1, beyond the free edge of the door 12, and 40 has pivotally mounted thereon a latch member 47, adapted to coact with a plate 48 secured to the door 11 adjacent the lower outer corner thereof. The latch 47 serves to retain the door 11 in position when closed. 45 The handle C is adapted to be locked, as shown in Figure 1, by any suitable locking device, as indicated at 49.

In operation, my improved mechanism works as follows, assuming the doors to be 50 in closed position, as indicated in Figure 3, and that it is desired to open the door: With the doors closed, the pin 34 upon the transmitting member 30 is disposed in the slot 45 of the keeper, and the handle C is secured to the door 12. When it is desired to open the door, the handle C is disengaged from the locking means 49 and swung outwardly from the door 12, causing a corresponding movement of the crank 22, which 55 bears upon the transmitting member 30 which is held against the wall of the slot in the keeper, continuous movement of the crank forcing the door 12 outwardly with reference to the door 11, the transmitting 60 member 30 during the initial movement of

the crank moving toward the left deeper into the slot 45 of the keeper, but after the crank pin has traveled a certain distance, the transmitting member is moved thereby in the opposite direction to a point where the pin 34 may be retracted from the entrance 46 of the slot and the door 12 swung fully open. When it is desired to close the door, a reversal of the above described operation takes place—that is, the pin 34 on the transmitting 70 member 30 is moved into the entrance 46 of the slot 45 and the handle C swung in a direction the reverse to that described during the opening movement, the initial movement of the crank causing a longitudinal movement of the transmitting member 30 and movement of the pin longitudinally within the slot 45, subsequent rotation of the crank portion causing complete closing movement 75 of the door.

By the above described arrangement, it will be noted that at the beginning of the door opening operation and at the end of the door closing operation, the direction of movement of the actuating force is mainly 80 transverse of the transmitting member 30, while at the beginning of the door closing operation, and at the end of the door opening operation, the movement of the crank is such that the movement of the transmitting member 30 is mainly longitudinal with respect thereto and with respect to the slot, thereby facilitating the engagement and disengagement of the pins 34 of the transmitting members with the related keepers F—F. 85

While I have herein shown and described what I now consider the preferred manner of carrying out my invention, the same is merely illustrative and I contemplate all changes and modifications that come within 90 the scope of the claims appended hereto.

I claim:

1. In a door operating mechanism, the combination with a member having a door opening and a pivoted door; of keeper means 100 fixed to the door frame adjacent the door opening, said keeper means being provided with recesses extending substantially parallel to the face of the door frame and having angular entrances thereto; of elongated 105 transmitting elements pivotally and slidably mounted on said door, and having actuating means upon their free ends adapted to engage in the recesses in said keepers; and means on said door for imparting longitudinal and lateral swinging movements to said transmitting members to effect opening and closing movement of said door.

2. In a door operating mechanism, the combination with a member having a door 120 opening and a pivoted door; of a rotatable shaft mounted on said door and provided with a crank portion; transmitting means movably mounted upon said door and having a pivotal connection intermediate its end 125

- portions with said crank, said transmitting means at one side of said pivotal connection being movably connected to said door, and being provided with elements at the other side of said pivotal connection adapted for engagement with keeper means secured to the door frame to effect opening and closing movements of said door upon rotation of said shaft.
3. In a door operating mechanism, the combination with a member having a door opening and a pivoted door; of a shaft rotatably mounted on said door and having an offset end portion projecting beyond the edge of said door; keeper means fixed to the door frame adjacent the edge of said door and having a longitudinally extending recess disposed substantially parallel to the face of said frame, and an angular entrance to said recess; and means for transmitting the movement of said crank to said keeper for effecting opening and closing movements of said door, said means being arranged to traverse said keeper longitudinally a greater distance at the inception of the door closing operation and at the finish of the door opening operation than during the remaining movement of said means, said latter movement being mainly lateral with reference to said first mentioned movement of said means and to the longitudinally extending keeper recess.
4. In a door operating mechanism, the combination with a member having a door opening and a pivoted door; of keepers fixed to the door frame adjacent the door opening; a rotatable shaft mounted on said door and having offset crank portions; transmitting members pivotally connected to the offset actuating portions of said shaft, said transmitting members each being provided with elements at one side of said offset portions adapted to coat with said keepers, and each of said transmitting elements having angularly projecting bosses upon the end thereof at the opposite side of said actuating portion; and housings on said door, each provided with a passage to permit sliding and swinging movements of the related transmitting member with respect to said housing, said housing being provided with offsets 50 adapted for engagement with said bosses to limit the outward movement of said transmitting members.
5. In a door operating mechanism, the combination with a member having a door opening and a pivoted door; of a shaft rotatably mounted on said door and having an off-set crank portion at one end; keeper elements fixed to the door frame and including means providing a longitudinally disposed recess extending substantially parallel with the face of said frame; and an elongated link having one end portion slidably and pivotally connected to said door adjacent its free edge, said link being pivotally connected intermediate its ends with said crank portion, and said link having adjacent its free end an actuating portion engageable with the recess in said keeper.
6. In a door operating mechanism, the combination with a member having a door opening and a pivoted door; of a shaft rotatably mounted on said door and having an off-set crank portion; a keeper fixed to the door frame adjacent the edge of said door and having means providing a longitudinally extending recess disposed substantially parallel to the face of said frame; and means for transmitting the movement of said crank to said keeper for effecting opening and closing movements of said door, said means being arranged to traverse said keeper longitudinally a greater distance at the inception of the door closing operation and at the finish of the door opening operation than during the remaining movement of said means, said latter movement being principally in a lateral direction with reference to said first mentioned movement of said means and to the longitudinally extending keeper recess.

In witness that I claim the foregoing I have hereunto subscribed my name this 19th day of November, 1925.

JOHN F. O'CONNOR.
